(57) **CLAIM**

The ornamental design for a display screen with a graphical user interface of an endoscope pitch indicator, substantially as shown and described.

DESCRIPTION

FIG. 1 is a front view of a first embodiment of a display screen with a graphical user interface for an endoscope pitch indicator;

FIG. 2 is a second embodiment thereof;

FIG. 3 is a third embodiment thereof; and,

FIG. 4 is a fourth embodiment thereof.

The broken lines showing the display screen form no part of the claimed design. The remaining broken lines showing portions of the graphical user interface form no part of the claimed design.
